DESIGN FOR A VEHICLE ORNAMENT

Edgard C. De Smet, Toledo, Ohio, assignor to Willys-Overland Motors, Inc., Toledo, Ohio, a corporation of Delaware

Application June 15, 1937, Serial No. 69,854

Term of patent 7 years

To all whom it may concern:

Be it known that I, Edgard C. De Smet, a citizen of the United States, residing in the city of Toledo, county of Lucas, and State of Ohio, have invented a new, original, and ornamental Design for a Vehicle Ornament, of which the following is a specification, reference being had to the accompanying drawing forming part thereof.

In the drawing, Figure 1 is a side view of the vehicle ornament showing my new design;

I claim:

The ornamental design for a vehicle ornament substantially as shown.

EDGARD C. DE SMET.
